POWER PLANT FOR OPERATING AN
ACCESSORYErwin C. Horton, Hamburg, N. Y., assignor to
Trico Products Corporation, Buffalo, N. Y.

Application July 13, 1936, Serial No. 90,448

13 Claims. (Cl. 60—60)

This invention relates to an accessory system for motor vehicles and more particularly to the generation of a pressure influence for utilization in operating the accessory.

5 Reduced atmospheric pressure or suction has been found to be a convenient and practical form of energy for operating a variety of automotive accessories, as for instance, windshield wipers, fuel pumps, horns, etc. This sort of energy has 10 been variously generated, some of the methods heretofore employed being the tapping of the intake manifold of an internal combustion engine, mechanical power take-off from moving parts of the running gear of a motor vehicle, 15 and the conversion of some source of fluid pressure available in a motor vehicle to subatmospheric pressure.

The present invention falls approximately in the latter class, in that the pressure or force of 20 a stream of oil from the lubricating system of an internal combustion engine, or similar source of such pressure or force, is used to drive a pump. The present invention aims to provide an improved accessory system wherein the pressure pump is operated in a practical and efficient 25 manner, and further to provide a pump structure which is readily accessible for repair and replacement.

The advantages of the present invention result 30 from the form or type of motor employed in connection with the pump, and the relative positions occupied by the motor and pump.

The use of an open turbine for driving the pump provides a driving mechanism which, 35 when the resistance offered by the pumped fluid through the medium of the pump becomes too great, merely ceases to operate, without strain, slippage or other detrimental or destructive effect on the mechanism.

40 When a rotary gear pump is used for pumping a gas some difficulty is encountered in effectively preventing adventitious escape of the gas between the gear teeth and between the face of the gears and the walls of the casing. To overcome 45 this objection various forms of seals, including fluid seals, have been devised. Through the relationship of the motor and pump in the present invention the sealing of the gear pump follows as a natural incident of that relationship 50 and no special provision for sealing need be provided.

In prior efforts to employ gear pumps for generating sub-atmospheric pressure it has been found that when the pressure is reduced beyond 55 a certain point, the surrounding atmosphere, in

its attempt to enter the area of reduced pressure in the pumping chamber, causes a popping noise which is often highly objectionable. The facility with which undue resistance in the pump arrests the movement of the driving turbine in 5 the present invention eliminates this objection to the use of a gear pump.

Simplicity of construction is another of many 10 additional advantages which result from this invention, one embodiment of which is shown in the accompanying drawing in which

Fig. 1 is a side elevation of an internal combustion engine including the instant device;

Fig. 2 is a side elevation of the combined 15 turbine and pump taken from the interior of the internal combustion engine; and

Fig. 3 is a cross sectional view taken on the line III—III of Fig. 2.

In the drawing, 10 designates generally an 20 internal combustion engine of the usual type having a crank case 11 and a force feed lubricating system (not shown).

The present invention is shown disposed in the 25 wall of the crank case 11 at 12, a position above the normal oil level 13 in the interior of the crank case.

A pump mounting member 14 is secured to the 30 outside of the crank case by screws 15 and effectively seals an opening 16 provided in the wall of the crank case 11. The pump may be 35 of an approved form, that illustrated embodying a pair of intermeshing gears 17 and 18 which are positioned approximately within the opening 16 and against the member 14 and are provided at their outer side with journals 19 bearing in 40 the member 14. A casing 20 is formed upon the inner side of the member 14 and extends inwardly and upwardly to form a pump chamber 45 for enclosing the lower halves of both gears about their point of mesh and thereadjacent where 40 their teeth come out of mesh. This formation exposes the upper portions of the gears for a purpose hereinafter set forth. The casing is formed at its upper end with a pair of bearings 21 for the inwardly extending journals 22 and 23 of the gears 17 and 18 respectively.

A suction or sub-atmospheric pressure conduit 24 is connected to the member 14 by means of a gland nut 25 which is screwed into a boss 26 formed upon the member 14. The conduit 24 communicates with a port 27 as well as a suction 50 operated accessory, such as a windshield cleaner (not shown), and it will be apparent that when the gears 17 and 18 are rotated clockwise and counter-clockwise, respectively, as 55

viewed in Fig. 2, air will be withdrawn from the accessory through the conduit 24 and discharged into the crank case 11.

The pump is driven by a motor, preferably a jet type motor, embodying a bladed wheel or turbine 28. This turbine wheel 28 is fixed to the journal 22 of gear 17 by means of threaded collars 30 and provided with impeller blades 29 extending in the direction of rotation.

10 A conduit 31 leads from some source of oil flowing under pressure, as in the pressure line of the engine force-feed lubrication system, and discharges a stream of oil against the impeller blades 29 through a jet 32. This stream of oil, when 15 it strikes the impeller blades 29, causes rotation of the turbine wheel 28 and the consequential operation of the pump. Before returning to the lubrication system at least a portion of the oil is delivered to the pump to seal as well as lubricate 20 the same for efficient operation. To this end the pump and the impeller blades are so arranged that a portion of the oil striking the impeller blades 29 is splashed or sprayed, as indicated at 25 33, upon the gears 17, 18 to provide an effective oil seal for the pump, as well as a thorough lubrication of the same. Attention is called to the fact that the air displacing member or members of the pump have their functioning parts exposed to the splashing oil so as to insure and assist 30 this mode of operation.

The jet 32 is fixed in a definite position in the engine, while the motor-pump unit is removable and replaceable through the opening 16. This facilitates the installation and renders the unit 35 readily accessible. Any oil entrained by the gears and brought into the pump chamber is subsequently returned to the crank case at the points where the teeth of the gears 17 and 18 leave the casing 20.

40 It will, therefore, be seen that, since the pump cannot operate without a discharge of oil from the jet 32, it will never be in operation without the presence of an adequate supply of oil for an effective fluid seal of the gear pump. Further, the 45 oil seal is maintained without the provision of special piping or conduits to convey the oil to the gears.

In case the pressure in the conduit 24 becomes 50 too low to be further reduced by action of the turbine wheel, either because the inlet to the conduit 24 is closed or restricted, or for any other reason, or if the resistance of the gear pump becomes excessive for any other reason, the oil stream will splash idly upon the impeller blades 55 and the turbine wheel 28 may slow down, stop, or even reverse itself, without any undue friction or strain being placed on any element of the device. The air displacing means of the pump, whether of the gear type or otherwise, are lubricated and 60 sealed efficiently. The gears, while depicted as being substantially half enclosed, may be more or less encased, but sufficiently opened to the splashing oil to obtain the desired operation. Furthermore, the upper halves of the gears may be 65 closed and the under halves exposed, or the axes of the gears may be disposed otherwise than in the same horizontal plane, provision being made to bring the exposed portions of the gears into the splashing oil.

70 In practice, the turbine and pump may be partitioned from the remainder of the crank case whereby the engine agitation of the oil bath will not hinder the operation of the turbine.

It will be seen from the above that an extremely 75 simple and highly efficient suction pump is pro-

vided. The particular arrangement and disposition of parts in the above description and in the drawing is, of course, merely exemplary, and the invention is not to be considered as limited thereby in any way excepting as defined in the appended claims. 5

What is claimed is:

1. In a motor vehicle power plant including an internal combustion engine having a circulatory lubricating system, a suction pump comprising a 10 casing, a pair of interengaging rotary pumping elements journaled in said casing, a turbine rotor mounted for rotation directly with one of said pumping elements and located in a position adjacent said pumping element, means for directing a flow of lubricant from the lubricating system against the turbine rotor to rotate the same, the spent lubricant, owing to the location of the turbine relative to said one pumping element, discharging upon the latter to provide a fluid seal for 15 said pumping elements.

2. In a motor vehicle power plant including an internal combustion engine having a circulatory lubricating system, a suction pump comprising a 20 casing, a pair of interengaging rotary pumping elements journaled in said casing, a turbine rotor of greater diameter than said pumping elements mounted for rotation and located in a position adjacent said pumping elements, means for directing a flow of lubricant from the lubricating system 25 against the turbine rotor with sufficient force to rotate the same and to splash therefrom, the casing opening into the splash whereby to lubricate said pumping elements and to provide a fluid seal for the same. 30

3. A motor vehicle power plant having an engine crank case with an opening in a wall thereof, a lubricating system for the power plant provided with a jet located in a predetermined position within the crank case and adjacent the 40 opening, and a jet operated air pump for supplying differential pressure to a pressure actuated accessory system, said pump being adapted to be positioned and secured in the wall opening in such manner as to close the opening and automatically dispose said jet operated air pump in proper operating relation with respect to said jet. 45

4. In a motor vehicle power plant having an engine crank case with an opening in a wall thereof, a lubricating system for the power plant provided with a jet located adjacent the opening and a jet operated air pump for supplying differential pressure to an accessory, said pump comprising a substantially flat plate for positioning over the opening in said crank case wall, and a casing disposed on the inner face of said plate, rotary pumping members journaled in said casing and a turbine rotor disposed coaxially with one of said pumping members and carried by said pump; the jet, the rotor and the plate means being so arranged and proportioned that securement of the plate means over the opening in the crank case wall automatically locates the turbine rotor in proper relation in the path of the stream of fluid from said jet. 55

5. In a suction pump for association with the crank case of an internal combustion engine comprising a plate member adapted to be positioned over an opening in the crank case wall, a pair of rotary intermeshing pumping elements mounted 70 against said plate member and journaled therein at one of their sides, an extension upon the plate member extending across the peripheries and portions of the sides of the gears at and adjacent their point of mesh, said extension being pro- 75

vided with bearings, journals at said other sides of the gears and disposed in said bearings, and a turbine rotor mounted upon one of said journals upon the opposite side of said bearings from said 5 pumping elements and adapted to be driven by a current of oil within said crank case.

6. In a suction pump for association with the crank case of an internal combustion engine comprising a pump chamber with an air port, an air 10 displacing member in the chamber, said chamber being open at one side, a bladed wheel mounted adjacent the pump chamber, and a jet for directing a stream of oil against the wheel to drive the same and with such force to splash over for 15 entering the open side of the chamber to lubricate the pump.

7. In a motor vehicle power plant including an internal combustion engine having a circulatory lubricating system, a suction pump comprising a 20 casing, an air displacing member having parts movable in sliding contact with the walls of the casing, a bladed wheel for operating the air displacing member, and means for directing a current of oil from the lubricating system against 25 the bladed wheel to rotate the same and splash therefrom, the casing being open at one part to receive a portion of the splashing oil for lubricating said displacing member.

8. In a motor vehicle power plant including an 30 internal combustion engine having a circulatory lubricating system, a suction pump operable for supplying low pressure to a suction operated accessory, said pump comprising a casing, an air displacing member therein and having sliding 35 contact with the inner wall thereof, a jet driven motor for operating said air displacing member, and means for directing a current of oil from the lubricating system to operate the motor and subsequently lubricate the air displacing member.

40 9. A motor vehicle power plant having an engine crank case with an opening in a wall thereof, a lubricating system for the plant provided with a jet located in a predetermined position within the crank case and adjacent the opening, and a 45 jet operated air pump for supplying differential pressure to a pressure actuated accessory system, said pump being detachably mounted over the wall opening to close the same and having a jet operated part disposed to receive a stream of oil 50 from the fixed jet.

50 10. A pumping system including a suction pump comprising a casing, a pair of interengaging ro-

tary pumping elements journaled in said casing, a turbine rotor mounted for rotation with one of said pumping elements and located in a position adjacent said pumping elements, and means for directing a jet of liquid under pressure against the turbine rotor to rotate the same, the spent liquid, owing to the location of the turbine relative to said pumping elements, discharging upon the latter to provide a liquid seal for said pumping elements. 5

11. In a motor vehicle power plant including an internal combustion engine having a circulatory lubricating system and a low pressure actuated accessory motor, a suction pump comprising a 15 casing, an air intake conduit leading from said accessory motor to said casing, and a pair of interengaging rotary pumping elements journaled in said casing, a turbine rotor of greater diameter than said pumping elements mounted for rotation and located in a position adjacent said pumping elements, means for directing a flow of lubricant from the lubricating system against the 20 turbine rotor with sufficient force to rotate the same and to splash therefrom, the casing opening into the splash whereby to lubricate said 25 pumping elements and to provide a fluid seal for the same.

12. In a pumping system, a suction pump operable for supplying low pressure to a suction operated accessory, said pump comprising a casing, 30 an air displacing member therein and having sliding contact with the inner wall thereof, a jet driven motor for operating said air displacing member, and means for directing a current of liquid against said motor to operate the same and 35 subsequently traverse the pump means to effect a seal between the air displacing member and the casing.

13. In a motor vehicle power plant including an internal combustion engine having a forced 40 liquid circulating system, a suction pump comprising a casing, a pair of interengaging rotary pumping elements journaled in said casing, a turbine rotor of greater diameter than said pumping elements mounted for rotation and located in 45 a position adjacent said pumping elements, means for directing a flow of liquid from the circulating system against the turbine rotor with sufficient force to rotate the same and to splash therefrom, the casing opening into the splash whereby to 50 provide a fluid seal for said pumping elements.
